RESPIRATOR APPARATUS

Ferdinand H. Terhaar, Los Angeles, Calif.

Application October 12, 1946, Serial No. 703,032

2 Claims. (Cl. 128—29)

1

This invention relates generally to therapeutic appliances, and relates more particularly to respirator apparatus or appliances of this character for use as an aid in improving pulmonary and systemic circulation and in the treatment of various ailments.

The apparatus in which this invention is embodied consists of a rigid two-part shell which may be of any suitable material, such as a transparent plastic or the like. The parts of the shell, when fitted together, surround the chest, and rubber seals or sheet bands are used to close off the openings against the body. This shell is then connected by a hose to a mechanical power unit, including a bellows, which is driven by an electric motor. This motor driven bellows drives air into and draws air from the shell through the hose, and creates alternately a negative and a positive pressure of air surrounding the chest, and the cycle may be synchronized with the patient's breathing. This has the effect of expanding the chest, when a negative pressure is created, causing the patient to inhale, and of compressing the chest, when a positive pressure is created, causing the patient to exhale. By suitably controlling the valves of the motor-driven pump mechanism, the breathing pulsations can be made so that the breathing will occur without effort, that is, the pulsations are timed to suit the respiratory rate of the patient, or the valves may be so controlled as to secure any other desired pulsation cycle having different breathing characteristics. It is therefore an object of the invention to provide a device having the above characteristics.

The parts of the shell are provided with a suitable seal between their adjacent edges, and it is necessary to also provide air seals between the arm and neck openings and the adjacent portions of the patient's body; and it is another object of the invention to provide an improved neck seal which is so constructed and arranged that it can be easily fitted to the neck of the patient, and may be adjusted to various neck sizes.

Another object is to provide a comfortable neck seal so that the patient experiences no discomfort even though remaining in the shell for protracted periods of time.

A still further object of the invention is to provide a neck seal which is substantially airtight against both inward and outward pressures.

These advantages result from the structural arrangement of the neck seal, which comprises two diaphragm-like portions, which are sealingly

2

secured to the respective upper and lower parts of the shell about the neck opening. The free end parts of each diaphragm extend outwardly of the neck opening and have portions that are folded inwardly to form envelopes, and the sides are clipped together close to the patient's neck and adjacent the shell.

It is still another object of the invention to provide a neck or throat seal which is simple in construction and effective in its functioning.

10 The shell is made considerably larger than the size of the patient which it is designed to accommodate, so that such patient is in no manner restricted or constricted. This shell extends to approximately the region of the patient's diaphragm, or somewhat below the lower ribs. Thus, the chest region is completely surrounded by the rigid shell or casing, but other parts of the body are free.

20 A shell of a given size is adapted to accommodate patients of various sizes, and it is, therefore, necessary to provide a waist seal which is adapted to be attached to different sized waists.

It is another object of the invention to provide a waist seal which will cause chest respiration and will not cause undesirable pressures on the patient's waist or abdominal region.

25 A further feature of the invention is to provide an arrangement of this character which may be secured to the patient without undue disturbance, and wherein the weight of the patient aids in effecting the seal.

In order to provide the above objects and features in the waist seal, said seal is constructed 35 of two thin sheets of elastic material, such as rubber or other soft elastic material, which is impervious to air. One sheet is attached to the bottom portion of the shell, and is so arranged as to be extended longitudinally therefrom. The other sheet is attached to the upper half of the shell in such a way that when the shell is placed over the patient in registration with the lower half, the second mentioned sheet extends over the abdomen of the patient. The sides of the upper sheet are tucked under the patient. The upper corners of the lower sheet are then drawn tightly about the lower edge portion of the shell, and secured by suitable means. Thereafter, the sides

40 of the lower sheet are brought up about the patient's body, and the sheets then secured by a suitable belt or belts, there being one belt adjacent the lower ends of the sheets, which is drawn about the patient's body, and another belt 45 which may be used about an intermediate portion

of the sheets. The tightness of these belts may be varied under various conditions.

The invention also contemplates the use of an extension or abdominal shield which may be detachably secured to the lower end of the upper half of the shell, and which produces abdominal respiration.

In order that the advantageous features of the invention may be fully understood, a brief reference to certain physiological facts concerning bodily circulation will be given. This circulation is governed in a large measure, by the same laws that control the flow of liquids in a closed system of cylindrical elastic tubes. The heart changes its shape and position with each breath. The movement of the ribs and the change in the elastic portion of the lungs are essential to the proper functioning of the pulmonary circulation. Further, proper diaphragmatic action is important for the return flow of the venous blood.

The circulatory system serves two primary purposes, the nourishment of the tissues and the removal of waste products. Any disturbance of its functions injures the tissues, even the heart muscle itself, either by gradual malnutrition or by slow intoxication.

The heart functions to distribute blood and the diaphragm assists in venous return. Damage to cardiac structure or interference with the normal excursion of the diaphragm has serious consequences to an individual's well being. It is a well-known fact in physiology that venous blood is drawn to the right side of the heart by the increase in negative thoracic pressure during inspiration, and the downward movement of the diaphragm, and is increased as the excursion becomes greater. This functional value is often lost through disease, which leaves the patient in a condition in which he cannot exercise this function to the extent of its normal value, hence aggravating his condition.

The action of the present device, as it affects circulation, can be summarized as follows: First, it controls the movement of the ribs and the downward pull of the diaphragm, thereby controlling the intra-thoracic negative pressure and influencing the venous return. Second, it alternately changes the atmospheric pressure surrounding the chest, to either above or below that which exists over the rest of the torso and which remains constant, thereby assisting the flow in the surface vessels upward and downward. Third, with each reduction of the atmospheric pressure over the chest, causing an inhale, the rubber bands over the abdomen and arms perform a massaging motion toward the heart, milking the surface vessels and releasing them when the pressure is reversed.

These three influences, accomplished mechanically, but without any particular consciousness on the part of the patient, give an impetus to the circulation, and the device has a multiplicity of uses. For instance, in respiratory failure, it can be used as a respirator. In surgery it is advantageous in post-surgical recovery or shock, or in pre-surgery preparation. In peripheral vascular disease it may be used to establish collateral circulation. In cardiac conditions, it may be used as an aid in supplying blood and oxygen to cardiac muscles, and it may be used to relieve splanchnic congestion. The foregoing are but a few of the uses to which the invention may be put.

Other objects and advantages of the invention

will become apparent from the following part of the specification.

Referring to the drawings, which are for illustrative purposes only,

Fig. 1 is a plan view of apparatus embodying the present invention arranged in a position for use on a bed, or the like, with the patient confined therein;

Fig. 2 is a longitudinal vertical section taken on line 2-2 of Fig. 1, showing the apparatus at that phase of the pulsation or operative cycle corresponding to an exhale;

Fig. 3 is a view similar to Fig. 2 showing another phase of the apparatus, that is, under conditions corresponding to the inhale phase;

Fig. 4 is a similar view but showing the application of the apparatus in a way to restrict pressure pulsation in the chest area of the patient;

Fig. 5 is a transverse vertical section taken on 5-5 of Fig. 1;

Fig. 6 is a transverse vertical section taken on line 6-6 of Fig. 2 showing the arrangement of the rubber sheets or aprons preparatory to securing them about the patient;

Fig. 7 is a longitudinal vertical sectional view showing the pocket portion of one of the parts of the neck seal;

Fig. 8 is a view of the apparatus as seen from line 8-8 of Fig. 1;

Fig. 9 is a vertical section taken on line 9-9 of Fig. 1;

Fig. 10 is a perspective view of the shell with the extension or abdominal shield attached thereto; and

Fig. 11 is a fragmentary longitudinal vertical sectional view similar to Fig. 2 illustrating the apparatus shown in Fig. 10, adjusted for use in subjecting the chest and stomach regions of a patient to pressure pulsations.

Referring more particularly to the drawings, the device comprises a shell or jacket of relatively light weight, rigid, transparent material, such as plastic, or the like, although any other suitable material may be used. The shell comprises a back part or half 10, and a front part or half 11, the back being shaped to conform to the human back for greater comfort. The parts are separated along a parting plane, and when assembled are sealed along this plane by a sealing gasket 12 between the adjacent edges of said parts. The sealing gasket may be generally U-shaped in cross-section, and attached to the free edge of one of the halves or parts of the shell, as shown in Fig. 5.

Means for securing the parts of the shell together is provided, and as shown, comprises clamps 13 positioned at suitable locations. As shown, there are two shoulder clamps, and a clamp at each side adjacent the lower end of the assembled shell. These clamps may be of any well-known type and, if desired, may be of such character as to permit quick locking of the parts together.

The shell provides a cavity or pressure chamber for reception of the upper portion of a patient's body, including the shoulders and chest, and the interior cavity of the shell is of considerably larger size than the size of the patient for which it is designed, so that the patient's body is in no manner restricted or constricted by the shell. If desired, different sized shells may be provided for the whole range of patient sizes and these shells may be nested, one within the other, to facilitate transportation of the devices. The

shell also has arm, neck and waist openings 14, 15 and 16 respectively, each portion (front and back) of the shell having a part defining substantially half of the respective openings.

When treating a patient it is necessary for the arm, neck and waist openings to be sealed, and the present invention provides means for this purpose. The arm openings, as shown, are sealed by tubular members or sleeves 17, are formed of flexible material, which is substantially impervious to air, such as rubber or some rubber-like composition, and are resiliently attached at one end of respective flanges 18 about the arm openings 14. The other end of the members 17 is adapted to fit about the arms 19 of the patient, and is brought into suitable sealing engagement with said arms by means of an elastic strap or ties 20, which are of rubber or the like, and are tightened to provide the proper degree of construction. One end of each tie 20 is secured, by vulcanizing or the like, to the respective sleeves, and said ties are wound about the outer ends of said sleeves. The free ends of the ties 20 are disposed beneath one or more wrappings thereof to prevent accidental loosening thereof.

The means for sealing the neck opening, which is considered as being at the top or upper end of the shell, comprises a pair of flexible sheet-like parts 22 and 23 of rubber, or other suitable material. The part 22 has its inner end portion secured within the front shell part 11 along the neck opening 15 by means of a generally semi-annular clamping member 24 attached adjacent the neck opening, screws 25 or the like being used for attaching the parts to the shell half 11. The member 22 extends outwardly of the neck opening 15, and its inner portion is reinforced so as to inhibit undue movement thereof under the influence of pressure pulsations. The end portion 26 of the member 22 is turned or folded inwardly, as best shown in Fig. 9, and the side edges 27 are secured to the adjacent side edges of the main body of the sheet so as to form an inwardly opening pocket 32 as shown in Fig. 7, for a purpose to be hereinafter described. The lower member 23 has its inner end portion similarly clamped by a semi-annular clamping member 28 attached to the body of the shell, adjacent the neck opening, by screws 29. The outer end portion of the member 23 has a part 30 which is folded inwardly and secured along its side edges in a manner similar to that of the part 26 of member 22. The patient's neck, of course, extends through the neck opening and the seal is rendered fully effective by means of clamps 31, which are clamped at the sides of the members 22 and 23 adjacent the patient's neck and adjacent the upper end of the shell, to provide the proper degree of construction without rendering the patient uncomfortable. The neck seal thus formed, is effective to prevent the passage of air either inwardly or outwardly of the neck opening. Inward pressure results when the pressure within the seal is below atmosphere and urges the parts 22 and 23 against the neck of the patient to prevent the entrance of air into the shell. When the pressure within the shell is above atmospheric pressure, there is outward pressure on the neck seal, and said pressure causes separation of the envelope parts so that the inturn portions 26 and 30 are pressed against the neck of the patient and prevent the escape of air from the device. Thus there is provided a very effective neck opening seal which causes the patient no discomfort.

If desired, a flange or bead 33 may be pro-

vided about the neck opening so that the edge thereof is rounded and smooth.

Means for sealing the waist opening 16, which is considered as being at the bottom or lower end of the shell, comprises a pair of sheet-like aprons, indicated generally at 35 and 36, for the back and front shell parts respectively. The aprons are of rubber or other suitable material, and from ten to fourteen inches wide and of sufficient length to extend to the lower end of the abdominal area. The upper edge portion of the rear apron 35 is disposed adjacent the lower end of the rear shell part 10 and is secured to said part along a limited intermediate section by means of a metal strip 37 and rivets 38. Extending laterally of the side edges of the apron 35, adjacent the attached end, are oppositely extending resilient straps 39, each of which has a metallic eye or ring 40 secured to the free end thereof, for a purpose to be hereinafter described. Adjacent the lower or free end of the apron 35 is an elastic belt or strap 41 of rubber or the like, which is secured at an intermediate portion to the outer side of the apron 35 as by vulcanizing or the like. The length of the belt 41 is substantially greater than the width of the apron 35 so that said belt may be passed about the body of the patient and secured. It is to be noted that one end of the belt 41 is provided with a metallic eye or ring 42, for use in securing the ends of said belt together. There is also provided an intermediate belt 43 of similar material, and said belt is secured at an intermediate part to the outer side of the apron 35 by vulcanizing, or the like. The belt 43 is also provided with a metallic eye or ring indicated at 44.

The front apron 36 is secured at a central portion of its upper edge to the lower edge portion of the front shell member 11, by means of a plate 45 and screws 46. The end portions of the plate 45 are turned outwardly to form hooks 47.

The front half 11 of the shell is provided with an opening 50, which may be described as being generally of keyhole shape, and is adapted to detachably receive a fitting 51 of well-known character, which is attached to a flexible air hose 52, leading from a suitable pumping mechanism 53. This pumping mechanism is of known type so that no further description thereof is deemed to be necessary.

If desired, a hole 54 similar to hole 50, may be provided in the rear shell 10, so that the fitting 51 may be attached to the back of the shell under certain conditions of use, as when it is necessary for the patient to lie face downward. One of the openings 50, 54, is closed by a plate 55 secured to the respective shell portion by screws 56. In the drawings, the hole 54 is shown as thus closed by the plate 55 inasmuch as the hose 52 is shown as being connected to the front shell portion 11. However, should the opening 54 be used for the hose connection, the opening 50 would be closed instead.

As above described, all of the opening seals are provided with their adjustable clamps and resilient ties and belts so that each may be secured about the respective arm, neck and waist members with just the right amount of pressure or constriction. The sealing bands of the arm and waist seals are adjusted so that, with the proper adjustment of the mechanism 53, to give the desired bellows pressures, each positive pressure pulsation will lift the resilient sealing bands with the result that a small amount of air escapes under the bands on each positive pressure pul-

sation. Thus, on each positive pulsation, a small amount of the air, and a corresponding fraction of the positive pressure, escape under the arm and waist seals. This serves the double purpose of relieving some of the positive pressure and making it lower than it otherwise would be, and causing a slow movement of air from the centrally-connected hose, through the shell and out through its several openings to thoroughly ventilate all parts of the patient's enclosed torso. A pad, not shown, may be provided on which the patient may lie, and said pad allows the air to extend the effects of ventilation to those parts of the body which may be resting thereon. And further, the ventilation action has the effect of periodically lifting the sealing bands from the patient's skin, ventilating those portions of the skin which would otherwise have their pores constantly sealed by the rubber band.

When the device is to be used, the rear shell portion 10 is disposed on a suitable support, such as a bed, indicated generally at 60, with the rear apron extended longitudinally therefrom and lying flat on the support 60. The patient is then placed in the rear shell part 10, and the front shell part 11 attached. The arm, neck and waist openings are then sealed.

In regard to the seals 17 for the arm openings, they are slipped over the arms and resiliently attached over the beads 18. Thereafter the ties 20 are secured. As to the neck opening, the clamps 31 are attached sufficiently close to the neck so as to form an airtight seal.

The apron 36 of the front shell portion 11 is draped over the patient's body, and the side edges 61 are tucked under so that the patient's weight aids in the formation of a tight seal. The strap portions 39 are then drawn up over the lower end portion of the shell, and the rings 40 secured to the hooks 41, as best shown in Fig. 5. The ends of the belt 41 are brought about the patient's body and secured by means of the ring 42, as shown in Fig. 1. In order to secure the belt in the adjusted position, the free end portion 62 is tucked beneath the adjacent portion of the belt. The belt 43 may be similarly attached. With two belts, 41 and 43, neither of said belts need be very tight in order to provide a suitable seal. However, under some conditions the belt 43 is loosely secured, for purposes to be hereinafter described, so that the belt 41 must be drawn sufficiently tight to provide a proper seal.

The above-described apparatus functions to control the movement of the ribs and the downward pull of the diaphragm, thereby controlling the intrathoracic negative pressure and influencing the return of venous blood; it also alternately changes the atmospheric pressure surrounding the chest to either above or below that existing over the rest of the patient's body, which remains constant, thereby assisting the flow in the surface vessels upwardly and downwardly. With each reduction of atmospheric pressure over the chest, causing an inhale, the seals over the arms, neck and abdomen perform a massaging motion toward the heart, milking the surface vessels and releasing them when the pressure is reversed. Further, when a partial vacuum is created in the shell, that is, when the pressure therein is below atmospheric pressure, blood is induced to flow back to the heart more quickly. In other words, the blood is drawn away from the feet and the brain, and in drawing the

blood away from the brain the possibility of a cerebral hemorrhage is greatly reduced.

It is to be understood, of course, that by various settings of the pumping mechanism, various effects can be produced on the blood stream, and various types of pathology may be treated.

Under some conditions, as where the patient has an abdominal surgical wound, the belt 43 is not drawn so tightly so that it does not put any pressure on the patient's abdomen, such an arrangement being shown in Figs. 2 and 3. This arrangement, which is used for chest breathing, shows, Fig. 2, distention of the apron 36 under the influence of positive super-atmospheric pressure within the device, the belt 43 limiting outward movement of the apron 36. In Fig. 3 the apron 36 is shown as being drawn inwardly under the influence of negative or sub-atmospheric pressure in the device. It will be apparent from the drawings that the abdominal wound, shown in Fig. 3, as being covered by a dressing 64, is not subjected to any mechanical pressure. In other words, the pressure on the stomach or abdominal portion of the patient's body, is an air pressure and not a mechanical pressure.

In Fig. 4 both the belts 41 and 43 are shown as being secured about the patient's body, the belt 43 not being drawn as tight as belt 41, but is drawn close to the abdomen. The advantage of this arrangement, as hereinabove pointed out, is that it is not necessary to draw either of the belts as tightly as is required where a single belt is used, and the massaging action is enhanced. Thus, the patient is subjected to less pressure from the secured waist seal. The arrangement shown in Fig. 4 is also used for chest breathing only, and in this arrangement, wherein two belts are used, there is an added massaging action in the region of the waist seal.

Due to the fact that in the present device the shell encompasses only the chest region of the body, patients may sit up in bed, or even stand upon the floor. Further, the device does not interfere with splints on the arms or legs.

For the treatment of some conditions it has been found desirable to provide abdominal breathing, and in order to induce such breathing with the present apparatus, a relatively rigid extension or abdominal shield 65 is provided, said shield being narrower at its free end 66 than at its attached end 67. The attached end 67 of the shield is curved to conform to the edge of the waist opening 16 defined by the front shell portion 11, and abuts against said edge. The sides 55 of the shield 65 are curved inwardly and toward the free end 66, which has an upwardly curved notch-like portion 68 to better conform to the patient's body.

The means for attachment of this shield to the front shell member 11 comprises a plurality of fasteners, each including a metal strip 69, secured to the adjacent portion of the shield by rivets 70. There is a fastener adjacent the sides of the shield 65, and an intermediate fastener adjacent the longitudinal center of the shield. Each fastener strip 69 has a slot 71, extending longitudinally from the free end thereof, for reception of bolts 72, which are received in holes provided therefor in the adjacent portion of the front shell part 11. The parts of the fastener strips 69 adjacent the slots 71, are received under heads 73 of the bolts 72, which are tightened by means of wing nuts 74. The strap 41 is fastened about the patient's body, as has already been described, while the strap 43 encompasses

the shield, it being understood that the apron 36 is disposed over the shield, and is also encompassed by the belt 43.

Adjustment of the free end of the abdominal shield 65 may be made, as indicated by the dotted line positions in Fig. 10, by positioning said shield as desired and then tightening the wing nuts 74. This adjustment is made possible by reason of the slots 71.

While the shell of the present device may be made of metal, such as aluminum or an alloy thereof, it has been found advantageous to form said shell of a clear or transparent plastic for the psychological effect on the patient who is generally conscious when being treated with the device. The patient thus knows that the attending physician can see what is happening within the shell and can take appropriate steps at all times to make any necessary adjustments of the apparatus.

I claim:

1. In apparatus of the character described: a rigid transparent shell defining a pressure chamber for reception of the chest portion of a person to be treated, said shell having arm, neck and waist openings; means for sealing the arm openings with respect to the arms of said person; means for sealing the neck opening with respect to the neck of said person; means for sealing the waist opening, said means comprising elastic front and rear aprons secured centrally along an edge portion to the front and back respectively of the shell adjacent said waist opening; means for securing said aprons in sealing engagement with the shell about the waist opening; and means for sealingly securing the free end portions of the aprons about the waist of said person.

2. In apparatus of the character described: a

rigid shell defining a pressure chamber for reception of the chest portion of a person to be treated, said shell comprising separable front and rear portions, and having arm, neck and waist openings; means for sealing the arm openings with respect to the arms of said person; means for sealing the neck opening with respect to the neck of said person, said latter means comprising a pair of front and rear sheet-like parts, each of which is connected to respective parts of the shell at the neck opening and have a portion, adjacent the free end thereof, turned inwardly and attached along its side edges to the adjacent edge portions of the rest of the sheet-like part, whereby inwardly opening pockets are formed in the neck seal; clamps for securing the associated edge margins of said sheet-like parts; and means for sealing the waist opening with respect to the waist of said person.

FERDINAND H. TERHAAR.
